(57) **CLAIM**

The ornamental design for a wireless charger, as shown and described.

DESCRIPTION

FIG. 1 is a front perspective view of the wireless charger showing my design.

FIG. 2 is a bottom rear perspective view of the wireless charger.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is an enlarged view of a encircled portion 9 shown in FIG. 1.

The evenly dashed broken lines shown in the drawings are for the purpose of illustrating portions of the wireless charger that form no part of the claimed design. The unevenly dashed lines shown in FIGS. 1 and 9 are for the purpose of illustrating the boundaries of the encircled portion, and form no part of the claimed design.
